Edward Wright
ATTORNEY

UNITED STATES PATENT OFFICE.

JOHN H. JORDAN, OF SCRANTON, PENNSYLVANIA^A

ELECTRIC-LIGHT-CONTROL SYSTEM.

1,241,520.

Specification of Letters Patent.

Patented Oct. 2, 1917.

Application filed February 21, 1917. Serial No. 149,999.

To all whom it may concern:

Be it known that I, JOHN H. JORDAN, a citizen of the United States, and a resident of Scranton, in the county of Lackawanna and State of Pennsylvania, have invented a certain new and useful Improvement in Electric-Light-Control Systems, of which improvement the following is a specification.

10 This invention relates to a system for controlling electric lights, and more particularly where such lights are temporarily or intermittently required. In apartment houses and other like places where there is 15 an all-night light service in the public halls, but only an occasional and temporary use of the light is required, a great saving may be effected by means of my improvement, which automatically extinguishes the lights 20 within a certain time interval after they have been turned on. The device is particularly adapted to be used in connection with a system where a time clock operates to shut off the lights in the public halls at 25 a predetermined hour, leaving a temporary light circuit in potential use, which is controlled by said improvement. This provides sufficient light for a person arriving or leaving late at night, after the main light circuit 30 has been turned off, to pass through the halls to or from the street, the temporary light circuit then being automatically turned off, and effecting a great saving in electric current, and a useless waste of burning these 35 lights all night, during which time there is seldom any occasion to use them.

40 My improvement may be carried out in various ways, by employing some form of mechanism operating automatically, after a certain time interval, to open the light circuit, and means for controlling the closing of the light circuit and the starting of said mechanism.

45 In the accompanying drawings: Figure 1 is a view, partially in elevation and partially in section, showing one form of mechanism which is employed in the preferred form of my improvement; and Fig. 2, a diagram of the circuits used in connection with 50 this form of mechanism.

55 Referring to Figs. 1 and 2, there is indicated a mechanism comprising a spring motor device or clock works, 7, having a spring, 8, and on the winding arbor, 9, of which is mounted a lever, 10, preferably of bell-crank shape, and having an arm connected

with the core, 11, of solenoid or coil, 12. The other arm of the lever carries a traveling contact, 13, adapted in one position to engage the contact, 14, of the light circuit, 15, and in another position to pass off the contact, 13, onto the insulation, 16, and open the light circuit. The solenoid is contained in another branch circuit, 17, having manually operated switches, 18, for opening and closing the branch circuit to the solenoid. The light circuit contains a number of lamps, 19, one or more being supposed to be located on each floor in the halls of a building, and the switches, 18, which may also be located 60 on each floor or at any convenient position for turning on the lights, are preferably of the push button type for momentarily closing the circuit, and then automatically opening the same when the hand is removed. 65

70 The spring 8, of the motor device or clock mechanism is partially wound up and operates the mechanism until the lever, 10, is moved by said mechanism against the rest or stop piece, 20, when the mechanism stops. 75 In this position of the lever, the light circuit is open. When the solenoid is energized, the core, 11, draws the lever, 10, away from the stop, 20, and down to a position in which the contact, 13, engages contact, 14, 80 and closes the light circuit. This movement of the lever also partially winds the clock mechanism which then starts into operation 85 the instant that the solenoid is deenergized. If, therefore, a person wishes to pass through 90 the halls, or for any other reason wishes to use the lights after they have been extinguished, he merely pushes one of the momentary switches, 18, which energizes circuit, 17, and the solenoid, 12, to actuate 95 the lever, 10, to close the light circuit, 15, and start the motor or clock mechanism into operation. This continues in operation during a certain time interval, or until the lever, 10, is moved back against the stop, 20, at 100 which time the contact, 13, has traveled on to the insulation, 16, and the light circuit is opened, thereby extinguishing the lights.

105 As the clock mechanism is partially wound by the movement of the lever at each stroke of the core of the solenoid, it does not require winding by hand, and needs no attention but is always ready for action.

Having now described my invention, what I claim as new and desire to secure by Letters Patent is:

110 1. In a time switch mechanism, the com-

- 5 combination of a switch, a lever positively attached to the movable member of said switch, a clock mechanism positively connected with said lever for moving the switch continuously from its closed position to its open position, a solenoid for actuating said lever to close the switch, and a hand operated switch for closing the solenoid circuit.
- 10 2. In a time switch mechanism, the combination of a switch, a lever having one arm carrying the movable member of said switch, a clock mechanism positively connected with said lever, and operating to move said switch continuously from its closed position to its open position, a solenoid connected to the
- 15 other arm of said lever, and a hand operated switch for closing the solenoid circuit.
3. In a time switch mechanism, the combination of a switch, a clock mechanism for opening said switch, a lever rigidly mounted on the winding arbor of the clock mechanism and carrying the movable member of the switch, a stop for said lever, a solenoid for drawing said lever away from the stop to partially wind the clock mechanism and to close said switch, and a hand operated switch for momentarily closing the circuit to the solenoid.

In testimony whereof I have hereunto set my hand.

JOHN H. JORDAN.
